(57) **CLAIM**

The ornamental design of a “digital display”, as shown and described.

DESCRIPTION

FIG. 1 is a front perspective view of our new, original and ornamental design for a digital display according to a first embodiment;

FIG. 2 is a rear perspective view of the digital display of FIG. 1;

FIG. 3 is a top plan view of the digital display of FIG. 1; FIG. 4 is a front elevational view of the digital display of FIG. 1;

FIG. 5 is a right side view of the digital display of FIG. 1; FIG. 6 is a left side view of the digital display of FIG. 1; FIG. 7 is a rear elevational view of the digital display of FIG. 1;

FIG. 8 is a bottom plan view of the digital display of FIG. 1; FIG. 9 is a perspective view of a digital display according to a second embodiment; and,

FIG. 10 is a front elevational view of the digital display of FIG. 9.

The broken lines shown in FIGS. 1-10 form no part of the claimed design.
